CLAIM

The ornamental design for a hugging weighted stuffed toy, as shown and described.

DESCRIPTION

FIG. 1 is a front perspective view of a hugging weighted stuffed toy showing my new design, with limbs and ears in an outstretched position;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof; and,

FIG. 8 is a front perspective view thereof, shown in a user environment with the hugging weighted stuffed toy in a hugging position.

The broken lines depicting portion of the hugging weighted stuffed toy in which the design is embodied form no part of the claimed design. The stipple shading as used in this application is a drafting convention used to show contrast with adjacent surfaces.
